UNITED STATES PATENT OFFICE.

ISAAC CHRIST, OF TAMAQUA, PENNSYLVANIA; WILLIAM H. CHRIST EXECUTOR OF
SAID ISAAC CHRIST, DECEASED.

SEPARATING APPARATUS.

1,196,750.

Specification of Letters Patent. Patented Aug. 29, 1916.

Application filed June 29, 1912. Serial No. 706,793.

To all whom it may concern:

Be it known that I, ISAAC CHRIST, a citizen of the United States, residing at Tamaqua, in the county of Schuylkill and State 5 of Pennsylvania, have invented new and useful Improvements in Separating Apparatus, of which the following in a specification.

This invention relates to apparatus for 10 separating the heavier mine products from the lighter, and has particular reference to that type of such apparatus generally termed jigs, in which the separation is effected by utilizing the differences in specific 15 gravity of the varying grades of material which are to be operated upon.

In jigging soft or bituminous coal, a very 20 large percentage of fine coal passes through the apertures of the jig pan into the water tank, and is carried off with the slate, bone or other impurities, resulting in quite a serious loss.

One of the objects of the present invention is to provide means for recovering the 25 finer particles of the high grade material which pass off with the impurities.

A further object is to provide an improved jig or separator adapted to stratify the different grades of material and to automatically 30 separate them in the course of its operation.

A further object is to provide means for providing a more perfect and complete separation of the high grade material from the 35 refuse.

The invention will be hereinafter fully set forth and particularly pointed out in the claims.

In the accompanying drawings: Figure 1 40 is a longitudinal sectional view of a separating apparatus embodying my invention. Fig. 2 is a plan view thereof. Fig. 3 is a transverse sectional view.

Referring to the drawings, 10 designates 45 a water tank provided at one end with wells 11 and 12, and at the other end with a similar well 13, the main portion of the tank having upwardly extended converging bottom walls 14, 15, the wall 14 being provided 50 with an overhanging portion 16. The upper edges of the tank are surrounded by a trough 17 which communicates with the wells 11 and 12 through channels 18.

The jig pan may be of any suitable construction but I prefer to employ the form

illustrated and described in Letters Patent 1,030,231, granted to Isaac and Henry K. Christ June 18, 1912. As illustrated the jig pan 20 is provided with bosses 21 to which are pivotally connected the crank arms 22 of a power shaft 23 supported in suitable bearing 24 mounted on the sides of the tank 10. Power is applied to the crank shaft 23 from any suitable source, as for instance a motor 25. In this manner an up and down movement is imparted to the jig pan and the latter is guided by guide members 21 which engage grooved guides 27 secured to the sides of the tank. The bottom of the pan is provided with perforations 28, and a discharge opening 29 is located at the forward end thereof and through which the heavier material is discharged. Said opening serves as the entrance to a pocket 30, the bottom of which is closed by a gate 31 pivoted at 32 and arranged to discharge toward the receiving end of the jig, said gate being suitably counter-balanced, as indicated at 31a. It will be noted that the bottom of the pan overhangs the pocket 30. The material is fed to the pan over a supply chute 33 secured to the upper edge of the rear or receiving end of the jig pan, and adjacent said chute is an adjustable gate 34, the space between said chute and said gate forming a receptacle within which all of the material to be separated and classified, is, at the outset, deposited.

The bottom wall 14 extends under the jig pan almost to the forward end of the latter 90 and all impurities, together with the finer particles of the more valuable materials which pass through the perforations 28 are directed by said bottom wall to the bottom of the well 13. From this point said materials are gathered up by a chain or bucket elevator 40 of any preferred construction and operated in suitable manner by the motor 25, the material being discharged by said elevator upon a chute 41 arranged to 95 direct the discharged material on top of the material already in the jig pan. The heavier particles that are directed into the pocket 30 are discharged by the gate 31 onto the bottom 15 which directs such material to a 100 second bucket elevator 43 which discharges the same at any suitable point. The finer particles pass over the upper edge of the jig pan into a discharge chute 44 which directs said material to the elevator 45 in the 105 110

well 12. It will be understood, of course, that all of the elevators are operated by suitable belt and pulley connections with the motor 25.

5 The operation is as follows:—The tank is filled with water to the desired depth, and the motor started to rotate the crank shaft 23. The effect of this rotation is to impart an up and down movement of the jig pan 10 while in the water, and while the jig pan is in motion, coal or other material, is fed over the chute 33 and passes beneath the gate 34. As the material is passed along the inclined bottom of the jig pan by reason of 15 the vibrations imparted in the reciprocation of the latter the heavier material tends to move toward the bottom and the lighter material to the top. The motion of the jig pan also forces the water through the apertures 28, further agitating the material and tending to turn the long pieces of slate or 20 heavy material parallel with the longitudinal line of the pan. As the operation progresses the slate and heavier material drop 25 into the pocket 30, the lighter material passing over the top of the pile and into the discharge chute 44. When the weight of the material in the pocket 30 becomes sufficient the gate 31 will drop and permit the 30 material in the pocket to be deposited upon the bottom wall 15. In handling fine material, however, such as bituminous coal it has been found that there is a very high percentage of loss by reason of the fine particles 35 of good coal passing through the perforations 28 with the slate and other refuse. Such material falls upon the bottom wall 14 and is directed to the elevator 40 by which it is raised and deposited upon a chute 41 40 which is arranged to direct the discharged material on top of the material already in the jig pan. Agitation of the jig pan will cause the heavier particles of this material to work down but will maintain the lighter 45 particles on top so that I am enabled to recover a very high percentage of material that would otherwise be wasted. In connection with the reciprocation of the jig pan an agitation or circulation of the water results 50 which eventually causes the latter to splash and overflow from the tank. To meet this condition I provide the trough to catch the overflow and a rigid guide in the well or compartment 12 serves to form a channel 55 18 which compels the water from the trough 17 to flow to the bottom of said compartment. The movement of the jig pan causes a circulation upwardly and forwardly and hence by discharging the water from the 60 trough at the forward end and near the bottom advantage is taken of the direction of circulation caused by the movement of the jig pan, to compel the overflow water to be included in the circulation, and not 65 remain stagnant in the troughs.

In connection with the foregoing I desire it to be understood that while I have described my invention as particularly adapted for the separation of soft coal I do not desire to limit myself in this particular as the 70 same may be utilized for separating other materials of different specific gravities without departing from the spirit thereof.

Having thus explained the nature of my invention and described an operative manner of constructing and using the same, although without attempting to set forth all of the forms in which it may be made, or all of the forms of its use, what I claim is:—

1. A separating apparatus comprising a tank, a jig pan mounted to reciprocate therein and provided with a perforated bottom, a supply chute for said jig pan, means for collecting material that passes through said perforated bottom, and means for depositing said material on top of the material supplied by said chute.

2. A separating apparatus comprising a tank provided with a compartment, a jig pan mounted to reciprocate in said tank and provided with a perforated bottom, a supply chute for said jig pan, means for directing the material that passes through said perforated bottom to said compartment, and means for depositing said material on top of the material supplied by said chute.

3. A separating apparatus comprising a tank provided with a compartment at one end, a jig pan mounted to reciprocate in said tank and provided with a perforated bottom, a supply chute for said jig pan, means for directing the material that passes through said perforated bottom to said compartment, and an elevator for depositing 100 said material on top of the material supplied by said chute.

4. A separating apparatus comprising a tank, a jig pan mounted to reciprocate therein and provided with a perforated bottom, said tank having an inclined bottom wall to catch material passing through said perforated bottom, a supply chute for said jig pan, and means for depositing said material on top of the material supplied by said chute.

5. A separating apparatus comprising a tank having upwardly extended converging bottom walls, a jig pan mounted to reciprocate in said tank and provided with a perforated bottom, one of said bottom walls being provided with an overhanging portion to catch material passing through said perforated bottom, a supply chute for said jig pan, and means for depositing said material on top of the material supplied by said chute.

6. A separating apparatus comprising a tank provided with a compartment, a jig pan mounted to reciprocate in said tank and

provided with a perforated bottom, said tank having an inclined bottom wall leading from said compartment to catch material passing through said perforated bottom, a supply chute for said jig pan, and an elevator in said compartment for depositing said material on top of the material supplied by said chute.

7. A separating apparatus comprising a tank having compartments at each end, a jig pan having a perforated bottom, means for directing the refuse material to one of said compartments, means for directing material passing through the perforated bottom of the jig pan to the other compartment, a supply chute for the jig pan, and means for depositing the last mentioned material on top of the material supplied by said chute.

8. A separating apparatus comprising a tank having compartments at each end and converging bottom walls extending to said compartments, a jig pan mounted in said tank and having a perforated bottom, one of the bottom walls of said tank being provided with an overhanging portion to catch material passing through the perforated bottom of the jig pan, means for depositing said material on top of the material normally fed to said jig pan, and means for depositing refuse on the other bottom wall.

In testimony whereof I have hereunto set my hand in presence of two subscribing witnesses.

ISAAC CHRIST.
